Primary Examiner — Gino Colan(74) *Attorney, Agent, or Firm* — thyssenkrupp North America, LLC(57) **CLAIM**

The ornamental design for a handrail, as shown and described.

DESCRIPTION

FIG. 1 an isometric view of a handrail showing our new design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in FIG. 1 represent environmental structure showing exemplary use of the handrail in an elevator car and form no part of the claimed design.
